United States Patent Office

Des. 183,722
Patented Oct. 21, 1958

183,722

CHAIR

Morton R. Cohen, Chicago, Ill.

Application February 29, 1956, Serial No. 40,413

Term of patent 14 years

(Cl. D15—1)

FIG. 1

FIG. 2

FIG. 3

Fig. 1 is plan view of a chair, showing my new design;
Fig. 2 is a side elevational view;

Fig. 3 is a front elevational view; and

Fig. 4 is a rear perspective view of said chair.

The characteristic features of the design reside in the rear frame and leg portions shown in full lines.

I claim:

The ornamental design for a chair, as shown and described.
